UNITED STATES PATENT OFFICE.

DANIEL O'HARA, OF WALTHAM, MASSACHUSETTS.

WATCH-CASE.

SPECIFICATION forming part of Letters Patent No. 316,814, dated April 28, 1885.

Application filed November 10, 1884. (Model.)

To all whom it may concern:

Be it known that I, DANIEL O'HARA, of Waltham, in the county of Middlesex and State of Massachusetts, have invented certain new and useful Improvements in Watch-Cases, of which the following is a full, clear, and exact description:

This invention relates to the construction of the various parts of a watch-case for their attachment to each other to secure the inclosure of the watch-movement, and under the invention, first, the band or ring to contain a watch-movement, arranged therein in the usual way or in any other suitable manner, is made with a bevel or taper at and across its exterior face or edge, and the central shell or body or annulus to surround and hold said movement-ring is made with a bevel or taper at and across its interior face or edge corresponding to the exterior taper of the ring, all in manner and form, with the ring placed and forced into the central shell to secure a jointing of the two sufficiently tight and close to attach the one to the other, and to prevent the entrance of dust and dirt and moisture at such joint; second, the central shell or movement-ring, or both, are made with either an exterior or an interior, or both an exterior and an interior, bevel or taper, and the other parts necessary to complete the inclosure of the movement in the movement-ring—such, for instance, as a front or a back bezel-ring or a front or back cap, cover, or plate—are made with a corresponding bevel or taper to suit the bevel or taper of the part of the annulus to which they belong, all in manner and form, with such parts placed in position and forced upon their proper parts of the central shell or movement-ring, as the case may be, to secure a jointing thereof sufficiently tight and close to attach them thereto, and to prevent the entrance of dust and dirt and moisture at such joints; third, the movement-ring is made with a bevel or taper at and across its exterior face or edge, and the central shell or body is made with a bevel or taper across its interior face or edge corresponding to the exterior taper of the ring, and otherwise made with a taper or bevel exteriorly or interiorly, or both, for receiving the other parts of the case necessary to complete the inclosure of the movement—such, for instance, as a front or a back bezel-

ring or a front or back cap, cover, or plate—which are correspondingly beveled or tapered, all in manner and form, with the several parts placed in position and forced upon their proper parts of the central shell, to secure a jointing thereof sufficiently tight and close to attach them thereto, and to prevent the entrance of dust and dirt and moisture at such joints; fourth, the central shell or movement-ring, or both, are made with either an exterior or an interior, or with both an exterior and an interior, bevel or taper and the other parts necessary to complete the inclosure of the movement in the movement-ring—such, for instance, as a front or a back bezel-ring or a front or a back cover or plate—are made with a corresponding bevel or taper to suit the bevel or taper of the part of the central shell or movement-ring to which they belong, all in manner and form, with such parts placed in position and forced upon their proper parts of the central shell or movement-ring, as the case may be, to secure a jointing thereof sufficiently tight and close to attach them thereto, and to prevent the entrance of dust and dirt and moisture at such joints, and, furthermore, made with a flange or rim in position to lap over the outer edge or periphery of the central shell sufficiently to conceal and close the joint between the parts of the case attached to the central shell or movement-ring, as the case may be; fifth, the winding key pipe or spindle or plug in its length is made of a conical or tapering shape, and a seat therefor in the central shell is made of a corresponding tapering or conical shape.

In the accompanying plates of drawings this invention is illustrated on an enlarged scale as carried out in various ways, all embracing its essential features of the taper and bevel jointing of the parts of the case to inclose the movement.

Figures 1 to 9, both inclusive, are cross-sections, Figs. 1, 2, 3, 4, and 9 being full, and Figs. 5, 6, 7, and 8 partial, sections. Figs. 10 and 11 are views in detail of this invention, illustrating it as applied to a stand or pedestal for supporting the watch-movement, which stand makes one part of the case.

In the drawings, A is the band or ring to contain the watch-movement. B is the central shell or body or annulus. C, Figs. 2, 4,

7, and 9, is the front bezel-ring, having a crystal, D; and E, Figs. 4 and 7, is the back bezel-ring, having a crystal, F.

In Figs. 1, 3, 6, and 8 crystals corresponding to the front and back crystals, D and F, carried by the front and back bezel-rings, C and E, of Figs. 2, 4, 7, and 9, are attached directly to the central shell, B—that is, without the interposition of bezel-rings—and in Fig. 10 a front crystal is similarly attached.

In Figs. 2 and 9 a back cap or plate or cover, G, is attached in Fig. 9 to the central shell, and in Fig. 2 to the movement-ring A, and this plate in Fig. 10 is carried by a stand 15 or pedestal, H. The movement-ring is made of a bevel or taper, J, at and across its outer face or edge, and the central shell is made of a corresponding bevel or taper, K, at its interior periphery or edge in the direction of 20 its width or thickness; and in Figs. 2, 3, 6, 8, and 9 this taper or bevel extends practically from side to side of the shell, and in Figs. 1, 4, 5, 7, and 10 it extends from one side, M, for only a part of the width of the shell, and 25 for the remaining part the shell tapers from the side N opposite to said side M toward and meeting the taper from that side N.

In Figs. 2 and 9 the front bezel-ring, C, is beveled or tapered at and around the inner 30 face of its flange or rim a, fitting over a corresponding taper or bevel, b, at and around the outer vertical face of a rim or flange, d, of the central shell in Fig. 9 and of the movement-ring in Fig. 2.

In Figs. 4 and 7 the front bezel-ring is beveled or tapered at and around the outer face of its flange or rim a, fitting within a corresponding taper or bevel at and around the inner periphery of the central shell and wherein 40 the movement-ring is placed.

In Figs. 4 and 7 the back bezel-ring is beveled or tapered at and around the outer face of its flange or rim f, fitting within a corresponding taper or bevel at and around the inner periphery of the central shell.

In Figs. 2 and 9 the back cap or plate is beveled or tapered at and around the inner face of its flange or rim g, fitting over a corresponding taper or bevel at and around the outer periphery of the central shell, Fig. 9, and of the movement-ring, Fig. 2.

In Figs. 1 and 8 the front and back crystals fit, by their outer beveled or tapered edge, within the corresponding bevel or taper at 55 and around the inner periphery of the central shell, and in Fig. 11 the same is true of the front crystal only, the back of the central shell being closed by the raised projection G on the upper face of the stand or support H, which 60 is beveled at and around its edge, fitting within the corresponding bevel or taper at and around the inner periphery of the central shell.

In Figs. 3 and 6 the front and back crystals fit, by the beveled or tapered inner face of their 65 rim or flange h, over the bevel or taper at and around the outer edge of the central shell.

In Figs. 2 and 7 the parts of the case cover-

ing the front and back sides of the central shell are provided with a flange or rim, k, which laps over the extreme outer edge or periphery of the central shell and conceals and covers up the joint made between such parts and the central shell.

In Fig. 8 the central shell is made in two parts, which are correspondingly tapered or 75 beveled, the one part around its outer edge or periphery, and the other part around its inner edge or periphery.

From the description given it is to be seen that the jointing of the several parts making 80 up the case is made by a taper or bevel of the contiguous faces thereof, which in all cases is made to correspond in manner and form to produce a tight and close jointing and attachment of them when they are placed in position 85 upon each other and forced to their seats. By this construction and jointing of the several parts when the parts are properly applied together a most secure and rigid attachment is obtained, excluding all entrance of dirt, 90 dust, and moisture, which, obviously, if the bearing-surfaces are ground will be increased in some considerable degree. At the same time the parts can be separated with readiness and ease when desired.

Set-screws may be applied to the several parts to rigidly fasten them; but they are not thought necessary or essential, as the tapering construction of the joints is sufficient for all practical purposes, and more especially so for 100 the purposes for which the improvements in watch-cases herein particularly described are to be used—to wit, for the casing and display of movements in the trade.

L² is the key pipe or spindle or plug, located 105 in the pendent knob M² of the case. This key-pipe L² is conical or tapering along a portion of its length, and this portion fits within a corresponding conical or tapering socket or tubular bearing, N², of the pendent knob.

In Figs. 1, 2, 6, and 9 the key-pipe passes through the movement-ring to engage with the movement, as ordinary, and for operation is turned around within the tapering or conical bearing N² therefor of the pendent knob.

In Fig. 4 the key-pipe is incased within a tapering or conical plug, O², which fits within a corresponding conical or tapering bearing of the central shell, B, and when it is to be used it, with said plug, is removed from the case, and it is unscrewed from the plug and entered through the conical bearing into the movement through a hole (not shown) in the movement-ring.

The taper of the key-pipe and of its bearing 125 within the pendent knob secures a close jointing and bearing between the two to the better exclusion of dirt, dust, and moisture to the watch-movement.

What I claim, and desire to secure by Letters 130 Patent, is—

1. In a watch-case, a movement-ring, A, having an exterior taper, and a central shell, B, having an interior taper and made sepa-

rate from each other and adapted to fit closely the one within the other, substantially as and for the purpose described.

2. In a watch-case, a central shell, B, and 5 the part of the case, such as a front or back cap or plate, or a bezel-ring and its crystal to close said central shell at its side, respectively made with tapering joints or surfaces and adapted to closely fit each other, substantially 10 as described, for the purpose specified.

3. In a watch-case, a movement-ring, A, and the part of the case, such as a front or back cap or plate, or a bezel-ring and its crystal to close said ring on its side, respectively 15 made with tapering joints or surfaces and adapted to closely fit each other, substantially as described, for the purposes specified.

4. In a watch-case, a movement-ring, A, having an exterior taper, J, and a central 20 shell, B, having an interior taper, K, and made separate from each other, in combination with a central shell, B, and the part of the case, such as a front or back cap or plate or a bezel-ring and its crystal to close the case on its 25 side, respectively made with tapering joints or surfaces and adapted to closely fit each other, substantially as described, for the purpose specified.

5. In a watch-case, a movement-ring, A, having an exterior taper, J, and a central 30 shell having an interior taper, K, and made

separate from each other, in combination with a movement-ring and the part of the case, such as a front or back cap or plate, or a bezel-ring and its crystal to close the case on 35 its side, respectively made with tapering joints or surfaces and adapted to closely fit each other, substantially as described, for the purpose specified.

6. In a watch-case, a front or back cap or 40 plate, or a bezel-ring and its crystal adapted to be attached to the case with a taper-joint, and constructed with a flange or rim, K, overlapping the outer edge or periphery of the central shell, substantially as described, for 45 the purpose specified.

7. In a watch-case having its several parts making the case proper adapted to be attached together with a taper joint or joints, the combination of a tapered socket, N², and 50 a tapered key pipe or plug, L², adapted to be entered into and to closely fit the taper of said socket, substantially as described, for the purpose specified.

In testimony whereof I have hereunto set 55 my hand in the presence of two subscribing witnesses.

DANIEL O'HARA.
